TOILET BOWL VENTILATOR

Filed March 21, 1934

FIG. I

Inventor

Raymond E. Fairchild

UNITED STATES PATENT OFFICE

2,023,127

TOILET-BOWL VENTILATOR

Raymond E. Fairchild, Palm Springs, Calif.

Application March 21, 1934, Serial No. 716,640

4 Claims. (Cl. 4—213)

My invention relates to improvements in toilet bowls and the object of my improvement is to provide a flue for conducting away the objectionable gases from a toilet bowl, and to provide a blower or suction unit for setting up a circulation in the flue. Among further objects is to provide means for making an electric circuit which shall automatically set the power unit in operation as soon as the toilet seat is occupied, and means for breaking the circuit when the seat is vacated.

10 In the drawing:

Figure I is a vertical section of the system,

Figure II is a sectional view showing the disengaged position of the rod which actuates the 15 electric switch, and

Figure III is the same in a position of actuation.

The toilet is of the usual type, having a bowl 1, an outlet conduit 2 leading through the floor 3, a pool of water 4, and a flushing pipe 5. To these 20 there is added flue 6 leading from the bowl 1 to the blower 7, thence to vent 8 in the wall 9, floor 3, or ceiling.

The toilet seat 10 is attached to the seat 1 by the hinge 12 in the usual manner. An electric switch 13 located in the block 11 is actuated by the rod 14 situated in a chamber hollowed from the seat 10. A lever 15 with fulcrum 16 is joined to rod 14 through link 17, and there is a coiled spring 18 encircling rod 14 and abutting at one 30 end upon a pin 19 in the rod 14, and at the other upon the wall of the chamber in the seat 10. The usual cover 20 is provided above the seat 10.

The spring 18 normally expands longitudinally and forces the rod 14 forward. This disengages 35 it from the electric button 21 of switch 13 and so breaks the circuit through wire 22 to the motor-blower 7. The expansion of spring 18 also normally acts through rod 14 and link 17 to force the lever 15 into a vertical position so that the 40 seat 10 is pried up somewhat from the rim of bowl 1, as shown in Figure II.

The weight of an occupant upon seat 10 causes the lower end of the angular lever 15 to glide forward upon the rim of bowl 1, and cause the upper 45 end through link 17 to force back the rod 14, compressing spring 18, and causing rod 14 to impinge upon button 21 of switch 13.

As long as the seat 10 is occupied, the electric contact is maintained and the blower 7 produces a current of air from bowl 1 through the flue 6 and out through vent 8, thus preventing any be- 5 fouling of air within the building.

I claim:

1. A toilet bowl having in combination a conduit leading from the bottom of said bowl, a pool of liquid in the bottom of said bowl, a flushing pipe entering near the top of said bowl, a flue leading 10 from the top of said bowl, motor means for producing a draft in said flue, a block above said bowl, a seat also above said bowl, a hinge joining said block and said seat, an electric switch in said block, a rod in a chamber of said seat, a spring 15 encircling said rod and tending to separate said rod and said switch, a link attached to the end of said rod, a lever attached to the end of said link, and an electric connection between said switch and said motor means. 20

2. Electric operating means for a toilet comprising a block attached to the top of a toilet bowl, a seat hinged to said bowl, an electric switch in said block, a rod in a chamber of said seat, a spring encircling said rod and tending to separate 25 said rod and said switch, a link attached to the end of said rod, a lever attached to the end of said link, and a flattened portion upon the rim of the toilet bowl for making contact with said lever. 30

3. A toilet having a bowl, a block attached to the rim of said bowl, a seat hinged to said block, an electric switch in said block, a rod in said seat for operating said switch, a spring encircling said rod, and lever means for converting the downward movement of said seat into the longitudinal 35 movement of said rod. 30

4. A toilet bowl having in combination, an inlet for flushing liquid; an outlet for gases, said outlet consisting of a tube rising vertically from the 40 bowl, thence passing horizontally over the mouth of said inlet and over the rim of the bowl, thence downwardly, and finally horizontally to a vent; and an electric fan within said outlet tube near the vent. 45
